Application April 10, 1942, Serial No. 438,422

8 Claims. (Cl. 90—21.5)

The present invention relates generally to machine tools, and more particularly to improved mechanism for actuating and controlling the movements of the work support and cross slide of a horizontal milling machine.

A general object of the invention is to provide improved means for controlling movements of the work support and cross slide through fluid pressure operated mechanism, to permit of convenient control of both elements at feed and traverse speeds through various operating cycles, both manually and automatically.

Another object of the invention is to provide in a milling machine of the above indicated type, a pair of members conveniently disposed for hand operation, whereby both the speed and direction of movement of the work support and cross slide can be manually controlled through functioning of the fluid pressure operated driving means, independently of the automatic control of the same driving means. In this way, the operator of the machine is enabled to obtain relative movement between the work and tool, preparatory to taking a cut without the expenditure of any physical effort, other than that required to manipulate the control handles. Provision is also made for complete hand control independently of the power means.

Another object of the invention is to provide an interlocking arrangement between the manual and automatic control elements, whereby operation of the fluid pressure actuated driving motor for either the work supports or cross slide is controlled wholly on a manual or automatic basis, without possibility of confusing the controls. That is to say, the automatic and manual controls for each power unit functioning entirely independently of each other, to the extent that either the work table or cross slide can be caused to travel at a desired speed and direction, under manual control, entirely irrespective of the existing speed adjustment of a unit.

The above and other advantageous features of the invention will hereinabove more fully appear from the following description considered in connection with the accompanying drawings, in which—

Fig. 1 is a view in front elevation of a machine embodying the invention.

Fig. 2 is a plan view of the machine shown in Fig. 1.

Fig. 3 is a side elevation of the machine shown in Fig. 1, as viewed from the right.

Fig. 4 is a development in perspective of the

manual and automatic controls for the power units.

Fig. 5 is a view partially in section of one of the power units.

Fig. 6 is a schematic view, illustrating the interlock between the manual and automatic controls, and related portions of the hydraulic circuit.

Figs. 7 and 8 are fragmentary views, illustrating details of the control mechanisms.

Referring first to Figs. 1 and 3, the invention is shown as being embodied in a milling machine comprising a bed 1, upon which is formed spaced horizontal ways 2 for supporting and guiding a work table 3. The table 3 is adapted to have a reciprocating movement imparted thereto on the ways 2, by means of a rotatably driven screw shaft 4 movable with the table and cooperating with a nut 5 carried by the bed, as indicated in dotted lines in Fig. 1. The means for controlling the speed and direction of rotation of the shaft 4 will be later described.

The bed 1 also provided spaced ways 6 extending at right angles to and above the table ways 2, and a cross slide 7 is movable back and forth on the ways 6 by means of a rotatably driven screw shaft 8. The front of the cross slide 7 provides spaced vertical ways 9, on which a tool head 10 is movable up and down, by means of a rotatably driven screw shaft 11. The tool head 10 provides a tool spindle 12, adapted to be rotatably driven at different speeds by means of a motor, located within and movable with the cross slide 7.

The essential elements of the milling machine described thus far are usual in machines of this character, and the present invention has to do with improved mechanism for controlling movements of the table 3 and cross slide 7, to cause

a tool mounted on the spindle 12 to perform the desired cutting operation on work mounted on the table. As will hereinafter appear, this control is such as to provide for either the feed or rapid traverse of both tool and work through various operating cycles, both manually and automatically, with all controls being readily accessible to the operator.

Referring now to Fig. 4, there is shown a development in perspective of the manual and automatic controls for the work table 3 and cross slide 7, which are indicated in dotted lines only, to show the relative positions of the parts. As will be evident from a comparison between Figs. 1 and 4, these controls are mounted on the front of the bed 1, which provides suitable panels 13

and 14 for supporting the controls in front of the table at a convenient height for the machine operator, with the controls for the table on the right-hand panel 13, as will next be described.

Referring to Fig. 4, the power units 15 and 16 for driving the table 3 and cross slide 7, respectively, are shown as being of the fluid pressure power transmission type, with each unit comprising a variable displacement pump, which delivers oil to a fluid motor of the same type. The particular power unit employed is of the general type commercially known as the Sundstrand "oil power" transmission, and so need not be described in detail at this point, other than to state that each unit 15 or 16 provides an input shaft 17 for the pump, and an output shaft 18 for the motor, hereinafter termed the motor shaft. The power units 15 and 16 are driven in unison through suitable gearing 19 from an electric motor 20 located inside a vertical portion 1a of the bed, which provides the ways 6 for the cross slide, see Fig. 3.

Since the power transmission units 15 and 16 are identical in construction and in operation, the manner of controlling the speed and direction of rotation of the output shaft of each unit is described in detail only with reference to the motor shaft 18, which is connected to the table feed screw shaft 4, as shown in dotted lines in Fig. 3. Referring to Fig. 5, the power unit 15 is shown with a portion of its control housing 21 in section, with a control stem 22 extending in the direction of the right-hand panel 13 on the machine bed 1. This stem 22 is movable longitudinally from the neutral position shown, to produce rotation of the motor shaft 18 in opposite directions. That is to say, when the stem is pulled out, clockwise rotation of the shaft 18, as viewed in Fig. 4, is produced; when the stem is pushed in, counterclockwise rotation results, with the shaft 18 being stationary when the stem 22 occupies a neutral or intermediate position.

The control mechanism also comprises rack plungers 23 and 24 connected by a pinion 25 turnable with a shaft 26. Normally, the plungers 23 and 24 are movable by hydraulic pressure, admitted to the rack cylinders by the above described shifting of the stem 22, either in or out. To operate the motor shaft 18 in a given direction, pressure is admitted to one of the rack cylinders to move one of the plungers from the neutral position shown, which has the effect of turning the pinion shaft 26 in one direction or the other, in accordance with whether the stem 22 is moved in or out and thereby move the other plunger in the opposite direction.

The speed at which the shaft 18 will be driven in one direction or the other, is controlled by the turning of a shaft 27 extending into the housing 21, and since the detailed construction of the power unit 15 forms no part of the present invention, it is sufficient to state that turning of the shaft 27 determines the angles of the elements 28 and 29 on the input and output shafts 17 and 18, respectively. These elements 28 and 29 are shown in dotted lines, and the angle which they make with the shafts 17 and 18 determines the length of the strokes of the pump and motor pistons, which are depended upon to transmit the power from the input shaft 17 to the output shaft 18.

Referring again to Fig. 4, the control stem 22 is connected by a link 30 to a two-arm lever 31, which is in turn connected by a link 32 to an arm 33 on a shaft 34, rotatably supported

by the bed 1 below the table ways 2. The shaft 34 extends through the panel 13, and carries at its end an operating handle 35. The linkage connecting the shaft 34 to the stem 22 is such that turning of the handle 35 will move the stem 22 in or out to cause rotation of the motor shaft 18 in one direction or the other, to thereby move the work table 3 through rotation of its feed screw 4.

10 The speed at which the table will move is determined by a knob 36 mounted on the end of a shaft 37 extending through the panel 13, and connected by couplings 38 and a link 39 to a shaft 40 mounted on the side of the control housing 21. The shaft 40 carries a gear 41, in mesh with a gear 42 mounted on the end of the speed adjustment shaft 27 of the power unit. Thus, the speed of the motor shaft 18, and consequently the rate of table feed, can be readily controlled by the knob 36, which is closely adjacent the table control handle 35, see Fig. 1.

15 The handle 35 is shown in its neutral position in Fig. 1, in which position the connecting linkage maintains the control stem 22 in its neutral position, with the motor shaft 18 stationary. By turning the handle 35 to the right or left feed position, the table 3 is caused to move to the right or left at a rate determined by the previous setting of the speed control knob 36. The extent 20 to which the table moves to the right or left, in accordance with the feed position of the handle 35, is determined by the setting of dogs 43 movable with the table, which are adapted to engage a lever 44 turnable with a shaft 45 extending beneath the table. The shaft 45 is connected by an arm 46 and link 47 to an arm 48 mounted on the inner end of the shaft 34. Consequently, when the table reaches either end of the stroke for which the dogs 43 are set, the lever 44 will 25 be turned to automatically cause stoppage of the table through the resulting movement of the control stem 22 to its neutral position.

30 Should it be desired to move the table at a rapid rate, for purposes of traversing, the handle 35 is moved to either one of two extreme positions, to the right and to the left of the feed positions 35 previously described. When the handle 35 is so moved, the stem 22 is moved to one extreme position or the other, whereby to operate a clutch 40 controlling gearing surrounding the shaft 18 and thereby step up the speed of the motor shaft 18 independently of the setting of the speed adjusting shaft 27. This mode of operation is inherent in the construction of the control mechanism of the transmission unit 15, and will be 40 described later with reference to Fig. 6.

45 As previously pointed out, the invention also contemplates the provision of a manual control for the work table that may be operated independently of the automatic control of the table, as determined by different positions of the handle 35. To this end, a handle 49 is provided on the panel 13, this handle 49 being in the form of an open grip extending somewhat above the table 3, where it may readily be held by the fingers of the operator.

50 The handle 49 is pivotally mounted on a hub 50, secured to the end of a shaft 51 rotatably mounted in a bracket 52 extending upwardly from the front of the panel 13, see Figs. 3 and 7. The shaft 51 carries a sprocket 53 connected by a chain 54 to a sprocket 55 forming part of a sleeve 56, freely turnable on the shaft 34 on which is mounted the automatic feed handle 35. The sleeve 56 provides a lateral arm 57 con-

nected by a link 58 that is supported for vertical movement in a bracket 59. The lower end of the link 58 is connected by a pin 60 to a lever 61 which extends from a hub 62, freely turnable on a shaft 63 extending at right angles to the shaft 34. The hub 62 provides a clutching element 62a which is adapted to cooperate with a clutching element 64 turnable with the shaft 63, and turning movement of the lever 61 by the handle 49 is imparted to the shaft 63 only when these clutch elements are engaged, see Fig. 6.

The end of the shaft 63 carries an arm 65 that is connected by a link 66 to the end of an arm 67 mounted on an extension of the shaft 26 carrying the pinion 25, which serves to connect the rack plungers 23 and 24 for movement in unison, although in opposite directions. Assuming that the feed control handle 35 and consequently the control stem 22 are in neutral position by reason of the connections previously described, and that the clutching elements 62a and 64 are in engagement, it is evident that turning of the handle 49 will cause the pinion shaft 26 to be turned independently of the control stem 22. The resulting movement of the rack plungers 23 and 24 in one direction or the other will therefore cause the motor shaft 18 to move the table to the right or to the left, in accordance with the direction of movement of the handle 49.

In order to prevent movement of the table 3 by the handle 49 during movement of the table under control of the handle 35, as during work feed, the arm 61 is always unclutched from the arm 65, except when the handle 35 is in its neutral position, as will later appear. Therefore, movements of the arm 67 in response to turning of the shaft 26 through movement of the control stem 22, are not transmitted to the manual control handle 49. For the same reason, accidental turning movement of the handle 49 during feed or traversing of the table under control of the handle 35, will have no effect on the operation of the power transmitting unit.

Referring now to Fig. 6, there is shown a schematic layout of the automatic interlock between the handles 35 and 49, to prevent their simultaneous control of table movement, as well as the hydraulic connections for control of the power transmission unit, in the manner outlined above. In this layout, the control stem 22 is shown in its neutral position, wherein the end of a plunger 68 is yieldingly maintained in a notch 69 provided in a collar 70 mounted on the stem 22. The opposite end of the plunger 68 carries a bridging member 71, which is maintained out of engagement with one pair of spaced contacts 72, while in engagement with a second pair of contacts 73. Upon movement of the stem 22 in either direction to move the table 3, the plunger will be forced out of the notch to open the contacts 73 and to close the contacts 72, the contacts remaining in this condition as long as the stem 22 is in any position other than its neutral position.

Conductors from the contacts 72 and 73 are adapted to be energized from a suitable source of electrical energy, as indicated, and a solenoid 74 controlling the clutching elements 62a and 64 is connected in circuit with the contacts 72. A second solenoid 75 is connected in circuit with the contacts 73, and this solenoid is adapted to control the position of a plunger 76, forming part of a throw-over valve 77 that is adapted to control the hydraulic circuit of the power trans-

mission unit 15. Therefore, with the stem 22 in its neutral position, the solenoid 75 is energized through closure of the contacts 73, with the solenoid 74 deenergized through opening of contacts 72.

The clutch device, previously described as being disposed between the arms 61 and 65, consists of the cooperating clutching elements 62a and 64 normally held in engagement by a spring 78 surrounding one end of the shaft 63. An L-shaped lever 79 provides a pin 79a engaged in a groove provided on the hub 62, while the opposite end of the lever is connected by a link 80 to a plunger 81 forming part of the solenoid 74. Consequently, energization of the solenoid 74, with the stem 22 out of its neutral position, will cause the lever 79 to swing to the right, as viewed in Fig. 6, and so disconnect the arms 61 and 65 through disengagement of the clutching elements. On the other hand, turning of the handle 35 to move the stem 22 into neutral position, will result in deenergizing the solenoid 74 to permit reengagement of the clutch, and resulting control of the rotation and speed of the motor shaft 18 by the handle 49, as will next be described.

As previously pointed out, the solenoid 75 provides a plunger 76 forming part of a valve 77 which is connected in the hydraulic control circuit of the power transmission unit 15. This control circuit is shown diagrammatically in Fig. 6, and with the solenoid 75 in a deenergized condition, the circulation of the hydraulic medium is entirely under the control of the stem 22, so as to determine the direction of rotation of the output shaft 18. Furthermore, with the solenoid 75 deenergized, the setting of the speed control knob 36 determines the speed of rotation of the shaft 18.

However when turning of the handle 35 moves the stem 22 to its neutral position, the resulting energization of the solenoid 75 causes the plunger 76 to move within the valve 77. Such movement of the plunger 76 causes the opening of two conduits 82 and 83, which allows a plunger 84 to float within a cylinder 85. This plunger 84 forms part of the transmission unit and its normal function is to determine the rate of speed of the output shaft 18 in accordance with the setting of a stud 86 turnable in and out with the speed adjustment shaft 27. However, the establishment of the hydraulic circuit through the conduits 82 and 83 by movement of the valve plunger 76 permits the plunger 84 to float in its cylinder, and thus have no effect on the movement of the rack plungers 23 and 24. That is to say, with the plunger 84 floating in the cylinder 85, the particular setting of the speed control shaft 27 has no effect in limiting movement of the rack plungers 23 and 24, as the latter may be actuated through turning of the pinion 25 by the shaft 26. Furthermore, when the solenoid 75 is energized, the position of the plunger 76 in the valve 77 is such as to block the several conduits that are used for starting, stopping and reversing the shaft 18 during normal operation of the unit under the control of the handle 35 and stem 22, thereby rendering these conduits inoperative during manual control of the unit by the handle 49.

Therefore, with the stem 22 in its neutral position, and with solenoid 75 alone energized through closed contacts 73, complete control of the direction and speed of movement of the table 3 is obtainable through the handle 49. By

turning the handle 49 to the right through a small angle, the table 3 will be caused to move to the right at a low speed, which can be increased by turning the handle farther to the right. The range of speed obtainable by movement of the handle 49 is the speed range normally obtainable within the power unit 15, by turning the elements 28 and 29 into different angular relations with respect to the input and output shafts 17 and 18.

Upon release of the handle 49 after causing the table 3 to be moved a desired amount, the handle will return automatically to its neutral position, by reason of the equalization of pressure on the rack plungers 23 and 24. The table 3 will then come to rest as the handle 49 returns to its neutral position, by reason of the fact that the motor shaft 18 is stationary, with the rack plungers 23 and 24 occupying the position of Fig. 5. However, as soon as the operator turns the handle 35 to cause feeding movement of the table by shifting of the control stem 22, the handle 49 is unclutched from the rack pinion shaft 26 through reenergization of the solenoid 74, as previously described. The table movement is then entirely under the control of the handle 35, and any accidental turning of the handle 49 will have absolutely no effect upon operation of the power transmitting unit, due to the fact that lever arms 61 and 65 are then disconnected by the disengaged clutch elements 62a and 64.

As previously pointed out, movement of the cross slide 7 with respect to the table 3 is adapted for manual and automatic control, in substantially the same manner as described with reference to the table. As best shown in Fig. 3, the second power unit 16 provides an output shaft 87 connected by a coupling 88, gearing 89 and a vertical shaft 90 to the screw shaft 8 extending between the ways 6 and engaging a nut 91 provided by the cross slide 7. The power unit 16 is identical in construction with the unit 15, and control of this unit 16 will next be described with reference to Figs. 4 and 8, which show opposite ends of the unit.

The control stem 92 for the unit 16 is connected by means of an arm 93 to one end of a rock shaft 94, the other end of which provides an arm 95 connected by a vertical link 96 to the end of a lever 97. The lever 97 is mounted to turn with an operating shaft 98, which extends directly through the control panel 14, in substantially the same horizontal plane as the shaft 34 carrying the feed control handle 35 for the table 3. The end of the shaft 98 carries a handle 99, turning of which is adapted to impart back and forth movement to the stem 92 to control the direction of rotation of the output shaft 87. Thus the handle 99 is adapted to control the direction of movement of the cross slide 7 by the screw shaft 8, in substantially the same manner as the handle 35 is adapted to control movement of the table 3. The speed at which the cross slide 7 will move under control of handle 99, is determined by a knob 100 mounted on the end of a shaft 101 extending through the panel 14, and connected through a coupling 102 to the speed adjusting stud 103 of the unit 16.

The handle 99 is shown in its neutral position in Fig. 4, in which position its connecting linkage maintains the control stem 92 in its neutral position, with the shaft 87 stationary. By turning the handle 99 to the right or left feed position, the cross slide 7 is caused to move to the right or left at a rate determined by the previous set-

ting of the speed control knob 100. The extent to which the cross slide 7 moves to the right or left, in accordance with the feed position of the handle 99, is determined by the setting of dogs 104 movable with the slide, which dogs are adapted to engage an actuator 105 turnable with a shaft 106. The opposite end of shaft 106 provides an arm 107 connected by a link 108 to one arm of a bell crank lever 109, the other arm of which is connected by a link 110 to an arm 111 mounted on the shaft 98 beyond the arm 97. Consequently, when the slide 7 reaches either end of the stroke for which the dogs 104 are set, the actuator 105 will be turned to automatically cause stoppage of the slide through resulting movement of the control stem 92 to its neutral position.

Should it be desired to move the slide 7 at a rapid rate, for purposes of traversing, the handle 99 is moved to either one of two extreme positions, to the right and to the left of the feed positions previously described. When the handle 99 is so moved, the control stem 92 is moved to one extreme position or the other, whereby to operate a clutch, not shown, controlling gearing surrounding the shaft 87, to thereby step up the speed of the shaft 87 independently of the setting of the speed adjusting knob 100. This mode of operation is inherent in the construction of the hydraulic control circuit of the transmission unit 16, and since the units 15 and 16 are identical, the schematic diagram, Fig. 6, is illustrative of the manner in which the rapid traverse speed is obtained through control of the pressure medium, in the conduits marked "Feed" and "Rapid."

The manual control for the cross slide 7 is obtained by means of a handle 112 mounted on the panel 14 above the feed control handle 99. The handle 112 is turnable with a shaft 113 connected by sprockets 114 and a chain 115 to a sleeve 116 freely mounted on the shaft 98. The sleeve 116 provides an arm 117 connected by a link 118 to an arm 119. This arm 119 is connected to an arm 120 through clutching elements similar to the clutching elements 62a and 64, as shown in Fig. 6. The arm 120 is connected by a link 121 to an arm 122 on the pinion shaft 123 of the unit 16, as shown in Fig. 8.

The clutching elements controlling connection between the arms 119 and 120 are adapted to be moved from engagement by a solenoid, not shown, the energization of which results from moving the stem 92 out of its neutral position. The stem 92 functions in exactly the same manner as shown with reference to the stem 22 in Fig. 6, to clutch the arms 119 and 120 together, with resulting control of the speed and direction of movement of the slide 7 being then determined entirely by movement of the handle 112. Since deenergization of the solenoid controlling the clutching elements or the arms 119 and 120 is accompanied by energization of a solenoid valve similar to the valve 77 in Fig. 6, the unit 16 behaves in the same manner as the unit 15, insofar as complete control thereof by the handle 112 is concerned.

In order to move the tool slide 7 by hand power alone, independently of the power unit 16, a shaft 124 is provided in the panel 14, the end of which is squared to receive a suitable crank 125, indicated in dotted lines. This shaft extends inwardly beneath the table, and is provided at its end with a sprocket 126 connected by a chain 127 to a similar sprocket 128 mounted on the forward end of the feed screw 8 for the slide 7.

Turning of the shaft 124 permits movement of the slide entirely by hand power, it being noted that the output shaft 81 of the unit 16 is free to rotate in either direction, with the handles 99 and 112 in neutral position. A similar shaft end 129 is provided in the panel 13 for moving the table 3 by hand power, the shaft being connected by suitable gearing, not shown, to the table feed screw 4.

From the foregoing, it is apparent that by the present invention there is provided an improved control mechanism for a machine tool of the milling machine type, whereby both the speed and direction of movement of the work support and cross slide for a tool can be manually controlled through functioning of the driving means, independently of the automatic control of the same driving means. Furthermore, the control is characterized by an interlocking arrangement between manual and feed control handles, whereby operation of the driving motor for either the table or cross slide is controlled wholly on a manual or automatic basis. This interlocking arrangement is such that with the automatic control handles 35 and 99 in neutral position as shown in Fig. 1, the operator can grasp both manual control handles 49 and 112 to cause movements of the table 3 and cross slide 7 in either direction and at speeds directly determined by the degree of turning of these handles. That is to say, the table 3 can be caused to move very slowly while the cross slide 7 is moved at a much greater rate, or vice versa, with the rate of these movements being entirely independent of the settings of the speed control knobs 36 and 100.

When the work table and cross slide have been moved to obtain the desired relation between work and tool preparatory to the beginning of a cut, release of the handles 49 and 112 immediately brings the table and slide to rest, and the handles 49 and 112 return to the neutral position shown in Fig. 1. Turning of either feed handle 35 or 99 then causes movement of either the table or cross slide at the particular rate determined by the setting of the corresponding speed control knob 36 or 100. It is to be noted that as soon as either handle 35 or 99 is turned from its neutral position, the interlock arrangement shown in Fig. 6 automatically unclutches the handle 49 or 112 from the pinion shaft 26 or 123 of the corresponding power unit 15 or 16. Therefore, accidental turning of either manual control handle 49 or 112 with either feed handle 35 or 99 turned from its neutral, or stop, position has absolutely no effect on the operation of the corresponding power unit.

We claim:

1. A milling machine comprising in combination a work table and a tool-carrying cross slide movable at right angles with respect to each other, rotatable screw shafts for moving said table and slide, separate motors for driving said shafts, pairs of motor control handles for causing said motors to move said table and slide through said shafts in different directions and at different set rates, and a manually operable handle for each motor extending above said table for directly controlling operation of each motor and thereby positively determining the direction and rate of movement of either table or cross slide, independently of any existing setting of the first-named speed control handles.

2. A control for machine tools comprising in combination a movable support, a rotatable driving element for moving said support, a variable

speed motor connected to said driving element, a motor control member movable from a stop position for determining the direction of movement of said support by said element, a second motor control member for regulating the speed of movement of said support by said element at set rates, and a third motor control member, normally maintained in a neutral position, for determining both the speed and direction of movement of said support by said driving element, independently of any setting of said second named control member, and only when said first named control member occupies its stop position.

3. A control for machine tools comprising in combination a movable support, a rotatable driving element for moving said support, a variable speed motor connected to said driving element, a motor control member movable from a stop position for determining the direction of movement of said support by said element, a second motor control member for regulating the speed of movement of said support by said element at set rates, and a third motor control member normally maintained in a neutral position, from which said member is turnable to independently determine the speed and direction of movement of said support by said driving element, whenever said first named control member occupies its stop position.

4. A control for machine tools comprising in combination a movable support, a rotatable driving element for moving said support, a variable speed motor connected to said driving element, a motor control member movable from a stop position for determining the direction of movement of said support by said element, a second motor control member for regulating the speed of movement of said support by said element at set rates, a third motor control member normally maintained in a neutral position, from which said member is turnable to independently determine the speed and direction of movement of said support by movement of said driving element, and means for preventing control of said motor by said third member when said first named control member occupies any position other than its stop position.

5. A control for machine tools comprising in combination a movable support, a rotatable driving element for moving said support, a variable speed motor connected to said driving element, a motor control member movable from a stop position for determining the direction of movement of said support by said element, a second motor control member for regulating the speed of movement of said support by said element at set rates, and a third motor control member normally maintained in a neutral position, with displacement of said control member from its neutral position serving to cause the movement of said support by said driving element at a rate of speed independent of the setting of said second named motor control member, and only when said first named control member occupies its stop position.

6. A control for machine tools comprising in combination a movable support, a rotatable driving element for moving said support, a variable speed motor connected to said driving element, a motor control member movable from a stop position for determining the direction of movement of said support by said element, a second motor control member for regulating the speed of movement of said support by said element at

set rates, and a third motor control member normally maintained in a neutral position, with displacement of said control member from its neutral position serving to cause the movement of said support by said driving element at a rate of speed independent of the setting of said second named motor control member, whenever said first named control member occupies its stop position, and with said third named control member always returning to its neutral position upon release thereof.

7. A control for machine tools comprising in combination a tool support, a work support, a rotatable driving element for moving one of said supports relative to the other, a variable speed prime mover connected to said driving element, a control member for said prime mover movable from a stop position, for determining the direction of movement of one of said supports by said driving element, a second control member for regulating the speed of movement of said support by said driving element at set rates, and a third control member for said prime mover, turnable from a neutral position, to regulate both the speed and direction of movement of said support by said driving element in accordance with the degree and direction of such turning by said third named control member, independent-

ly of any prior setting of said second named control member, and only when said first named control member occupies its stop position.

8. A control for machine tools comprising in combination a tool support, a work support, a rotatable driving element for moving one of said supports relative to the other, a variable speed prime mover connected to said driving element, a control member for said prime mover movable from a stop position, for determining the direction of movement of one of said supports by said driving element, a second control member for regulating the speed of movement of said support by said driving element at set rates, and a third control member for said prime mover, turnable from a neutral position, to regulate both the speed and direction of movement of said support by said driving element in accordance with the degree and direction of such turning by said third named control member, independently of any prior setting of said second named control member, and interlocking means between said control members for preventing movement of said support by accidental turning of said third control member, while said support is moving under control of said first named member.
